(57) **CLAIM**

We claim the ornamental design for a chase, as shown and described.

DESCRIPTION

FIG. 1 is a perspective view of a chase;

FIG. 2 is a first side view thereof;

FIG. 3 is a second side view thereof;

FIG. 4 is a first end view thereof;

FIG. 5 is a second end view thereof;

FIG. 6 is a top view thereof; and,

FIG. 7 is a bottom view thereof.

The broken lines depict portions of the article that form no part of the claimed design.

The chase is shown broken away to indicate that it has no specific length other than the one shown.
